US00D785016S

(12) United States Design Patent (10) Patent No.: US D785,016 S
Berwick et al. (45) Date of Patent: * Apr. 25, 2017

(54) DISPLAY SCREEN WITH GRAPHICAL USER INTERFACE

(71) Applicant: Deutsche Bank, New York, NY (US)

(72) Inventors: Sarah Berwick, Short Hills, NJ (US); Boris Fuzayloff, East Brunswick, NJ (US); Melody Browne, Atlantic Highlands, NJ (US); Thomas Lukoma, Parlin, NJ (US); Yakov Manukyan, East Brunswick, NJ (US)

(73) Assignee: Deutsche Bank AG, New York, NY (US)

() Term: 14 Years

(21) Appl. No.: 29/494,643

(22) Filed: Jun. 23, 2014

(51) LOC (10) Cl. 14-04

(52) U.S. Cl.

USPC D14/486

(58) Field of Classification Search

USPC D14/485-495

CPC . G06F 3/0481; G06F 3/0482; G06F 17/30572

(57) CLAIM

The ornamental design for a display screen with graphical user interface, as shown and described.

DESCRIPTION

The FIGURE is a front view of a display screen with graphical user interface.

The outermost broken line showing of a display screen illustrates environmental structure, and forms no part of the claimed design. The remaining broken lines illustrate portions of the graphical user interface, and form no part of the claimed design.
